US0D1092413S

(12) **United States Design Patent** (10) **Patent No.:** **US D1,092,413 S**
(45) **Date of Patent:** **** Sep. 9, 2025**

(54) **HOUSING OF CONTROLLER**

(71) Applicant: **SONY INTERACTIVE ENTERTAINMENT INC.**, Tokyo (JP)

(72) Inventor: **Daisuke Kurihara**, Chiba (JP)

(73) Assignee: **SONY INTERACTIVE ENTERTAINMENT INC.**, Tokyo (JP)

(**) Term: **15 Years**

(21) Appl. No.: **29/883,055**

(22) Filed: **Jan. 23, 2023**

(30) **Foreign Application Priority Data**

Aug. 5, 2022 (CN) 202230508377.3

(51) **LOC (15) Cl.** **21-01**

(52) **U.S. Cl.**

USPC **D21/333**; D14/401

(58) **Field of Classification Search**

USPC D13/168; D14/218, 388, 356, 400, 401, D14/402, 405, 412, 415, 416, 426, 432, D14/454; D21/333, 324, 328

CPC A63F 13/00; A63F 13/02; A63F 13/12; A63F 13/23; A63F 13/24; A63F 13/26; A63F 13/98; A63F 9/02; A63F 9/029; A63F 9/0291; A63F 9/0252; A63F 9/24; A63F 2300/00; A63F 2300/1031

See application file for complete search history.

CLAIM

The ornamental design for a housing of controller as shown and described.

DESCRIPTION

FIG. 1 is a front perspective view of a housing of controller showing a first embodiment of my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 4 Drawing Sheets
